DESIGN FOR SUNGLASSES

Julius Hommer, Newark, N. J., assignor to Lapin Products, Inc., New York, N. Y., a corporation of New York

Application April 3, 1940, Serial No. 91,430

Term of patent 14 years

To all whom it may concern:

Be it known that I, Julius Hommer, a citizen of the United States and residing at Newark, in the county of Essex and State of New Jersey, have invented a new, original, and ornamental Design for Sunglasses, of which the following is a specification, reference being had to the accompanying drawing, forming part thereof, and in which

Fig. 1 is a front elevational view of sunglasses showing my new design,

Fig. 2 is a top view, and

Fig. 3 is a side view of the same, a part of the temple being broken away for convenience of illustration.

The distinctive characteristic feature of the present design resides in the provision of a shield forming part of a hemisphere, the base of the hemisphere of which is formed by the rim of the sunglasses and said shield consisting of a section of such hemisphere terminating above the center horizontal plane through the rims of the sunglasses. The forward edge of the shield on each rim curves upwardly and outwardly from adjacent the inside edges of the sides of the rim.

I claim:

The ornamental design for sunglasses, substantially as shown and described.

JULIUS HOMMER.
